US00D674749S

(12) **United States Design Patent**
Moore et al.

(10) **Patent No.:** US D674,749 S
(45) **Date of Patent:** ** *Jan. 22, 2013

(54) **BATTERY LABEL**

(75) Inventors: **Shannon Tyler Moore**, Waterloo (CA);
Andrew Yiu Wah Tam, Waterloo (CA);
Kevin Roy Sugden, Toronto (CA)

(73) Assignee: **Research In Motion Limited**, Waterloo,
Ontario (CA)

(*) Notice: This patent is subject to a terminal disclaimer.

(**) Term: **14 Years**

(21) Appl. No.: **29/408,929**

(22) Filed: **Dec. 19, 2011**

(51) **LOC (9) Cl.** 13-02

(52) **U.S. Cl.** **D13/119**

(58) **Field of Classification Search** D13/102-106,
D13/110, 118-119, 184; 429/96-100, 163,
